HYDRAULIC TRANSMISSION APPARATUS

John S. Becker, Poughkeepsie, N. Y., assignor to
Bendix Aviation Corporation, Teterboro, N. J.,
a corporation of Delaware

Original application November 23, 1942, Serial
No. 466,640. Divided and this application
August 22, 1944, Serial No. 550,651

1 Claim. (Cl. 60—54)

1

This invention relates to hydraulic apparatus and particularly to the establishment and control of a hydraulic type of driving connection or transmission for transfer of energy from a driving member to a member to be driven.

An object of the invention is to provide a novel type of hydraulic transmission characterized by the ability of the mechanism to adjust itself automatically to variations in the conditions imposed thereupon, and in such a manner as to produce, at the driven end of the unit, a substantially constant speed or a substantially constant torque output, according to which is preferred in any given installation.

Another object of the invention is to provide a novel hydraulic transmission of the type including a pair of fluid receiving members rotatable about a common axis and adapted to occupy varying relative positions in response to variations in the speed of the driving member.

These and other objects of the invention will become apparent from inspection of the following specification when read with reference to the accompanying drawing wherein an elected embodiment of the invention is illustrated. It is to be expressly understood, however, that the drawing is for the purpose of illustration only, and is not designed as a definition of the limits of the invention, reference being had to the appended claim for this purpose.

In the drawing:

Figure 1 is a longitudinal sectional view of the invention.

Figure 2 is a transverse sectional view taken on the line 2—2 of Figure 1.

In practicing my invention, as illustrated in the drawing, I employ a housing 4 having complementary sections 5 and 6 provided with registering flanges 7 and 8 suitably secured as indicated at 9, and further provided with hub portions 11 and 12, respectively, the former being journaled upon a driving shaft 13, as indicated at 14, while the hub 12 is drivably connected by means of a key 16 to a driven shaft 17; the latter being counterbored to form a bearing portion 19 to receive the reduced end portion 21 of the driving shaft 13.

Within the housing 4 there is provided a fluid receiving vessel or member 26 provided with radially disposed vanes 28. The housing section 6 is equipped with radially disposed vanes 61 which together with the section 6 constitutes a driven rotor or member 60 which together with the member 26 provide complementary impellers or rotors with the disposition thereof being such

2

that upon rotation of the driving shaft 13 (and therefore corresponding rotation of the driving member 26, which is keyed to the shaft 13, as indicated at 31) liquid within the housing sections 5 and 6 will be picked up by the pockets formed in the impeller 26 by the vanes 28 and thrown from said pockets against the vanes 61 of the rotor 60, thereby causing a rotation of the housing 4, thus producing rotation of the driven shaft 17.

The novel means whereby the speed of rotation of the driven shaft 17 is maintained substantially constant, notwithstanding variation of the speed of the drive shaft 13, resides in the vanes 61 being angularly spaced and having their outer and inner ends pivotally mounted in bearings 62 and 63, respectively, formed integral with the housing section 6, as illustrated in Figure 1. The vanes 61 are of an L-shaped configuration in cross-section and each has one face engaged by a pair of coiled compression springs 67. The springs bear against the wall of the housing section and tend to hold the vanes in the relative disposition indicated in Figure 1, namely, in approximate alignment with the oppositely disposed vanes 28 of the driving impeller 26; but as the speed of rotation increases—which increased speed would otherwise create a tendency for a correspondingly increased torque output at the driven shaft 17—the resulting increase in fluid pressure exerted against the vanes 61 will tend to turn the said vanes about their bearings 62 and 63 thereby producing a greater degree of compression of the springs 67. As such turning of the vanes occurs the amount of relative rotation or slip, as between the driving impeller 26 and the driven vanes 61, will increase due to the increase in the gap between the opposing edges of the vanes 28 on the one hand and the now receding edges of the vanes 61 on the other. This increase in slip will in turn reduce the fluid pressure being exerted upon the vanes 61, thereby offsetting what would otherwise be the tendency toward increased torque at the driven shaft 17. Thus is produced an action by reason of which torque output at the driven shaft 17 is maintained substantially constant.

This is a division of my application Serial Number 466,640 filed November 23, 1942.

What is claimed is:

In a hydraulic transmission, the combination of a fluid tight housing adapted to contain fluid; a driving impeller member rotatably mounted at one end of said housing; a driven rotor member rotatably mounted at the other end of said hous-

ing and in predetermined spaced relation with respect to said impeller member; and fluid pressure responsive means for varying the space relationship between said members, said means including a plurality of substantially L-shaped vanes arranged in angular spaced relation about the axis of rotation of said driven member and pivotally connected at both ends to the latter, each of said L-shaped vanes having an inwardly extending leg, the end face of which is in parallel spaced relation with the adjacent end face of said impeller member and a laterally extending leg in substantially parallel spaced relation with

the adjacent end wall of said housing; and a plurality of springs for each L-shaped vane and in radial spaced relation relatively, said springs disposed between said laterally extending leg and the adjacent housing end wall for yieldingly urging said inwardly extending leg toward said impeller member, the displacement of said inwardly extending legs being variable to compensate for differences in speeds of rotation of said impeller member without imparting consequent changes in the speed of rotation of said rotor member.

JOHN S. BECKER.
